3 Claims. (Cl. 321—69)

(Granted under Title 35, U.S. Code (1952), sec. 266)

The invention described herein may be manufactured and used by or for the Government for governmental purposes without the payment to us of any royalty thereon.

This invention relates to microwave devices in general, and more particularly to a microwave cavity device for frequency doubling.

It is the object of this invention to provide a frequency-doubling microwave cavity device.

In a typical embodiment, the frequency-doubling cavity device comprises a ferrite loaded cavity excited in the resonant TM_{110} mode by an input signal of frequency f , with a D.-C. magnetizing field applied to the ferrite within the cavity. The position of the ferrite, the strength and direction of the D.-C. magnetizing field, and the cavity dimensions are chosen so that a double frequency component is produced which excites the cavity in the resonant TE_{012} mode, thereby permitting a double frequency signal to be obtained at a properly located output.

The specific nature of the invention, as well as other objects, uses, and advantages thereof, will clearly appear from the following description and from the accompanying drawing, in which:

FIGURE 1 is a longitudinal pictorial view of a microwave frequency-doubling cavity device in accordance with the invention. A portion of the cavity wall is cut-out to reveal the disposition of the ferrite within the cavity.

FIGURE 2 is a sectional view along 2—2 in FIGURE 1.

It has been theoretically derived and experimentally verified that, when a microwave magnetic field is incident on a ferrite or other insulating ferromagnetic material in a manner such that the R.-F. field has a component perpendicular to the direction of D.-C. magnetization of the ferrite, second order components of magnetic flux at double the R.-F. frequency will be produced in the ferrite in the direction of the D.-C. magnetization. (See (1) Journal of Applied Physics, vol. 27, February 1956, pp. 188-189, and (2) Proc. IRE, vol. 44, August 1956, p. 1054.) This second order frequency-doubling effect has heretofore merely been a laboratory curiosity and it was not believed that the effect could practically be employed for frequency doubling. In the present invention, this effect is employed in a novel and practical frequency-doubling cavity device as illustrated in the drawing.

In FIGURE 1, a cylindrical cavity 10 is excited in the TM_{110} mode by a microwave input at frequency f coupled to the cavity 10 by means of a waveguide arm 14 and an iris 17 in a conventional manner. As is well known in the art, the resonant frequency of a cavity excited in the TM_{110} mode is dependent only upon its diameter D and is independent of its length L . This feature is very advantageously used in the present invention as will be brought out later. The field pattern 25 of a cross section in the TM_{110} mode is shown by the dashed lines in FIGURE 2.

A ferrite rod element 19, preferably having a diameter which is considerably smaller than the diameter of the cavity 10, is disposed along the longitudinal axis of the cavity 10. Supporting members 22 and 24 of insulating material such as Teflon may be used to support the ferrite element 19. Means are provided, which are also well known in the art, for applying a D.-C. magnetizing field

2

H_{d-c} to the ferrite 19 in a direction parallel to the longitudinal axis of the cylindrical cavity 10. The means for applying, and the magnetizing field are represented by the symbol H_{d-c} and the arrow 21 in FIGURE 1. The ferrite element rod 19 may alternatively be a sphere, an ellipsoid, or any other suitable shape.

As can be seen from FIGURES 1 and 2, the R.-F. magnetic field at the input frequency f is perpendicular to the direction of D.-C. magnetization H_{d-c} of the ferrite element 19. As described previously, this will produce second order components of magnetic flux in the vicinity of the ferrite element 19 at double the R.-F. input frequency, and in a direction along the longitudinal axis of the cavity 10. These second order double-frequency components of magnetic flux are advantageously used in the present invention by choosing the dimensions of the cavity 10, the position of the ferrite element 19 along the axis, and the strength of the D.-C. magnetizing field H_{d-c} , so that the double-frequency magnetic flux excites a resonant mode in the cavity 10. A series of such possible modes in the cavity 10 are the TE_{0nm} modes where "n" and "m" are any integers other than zero. These TE_{0nm} modes are suitable because they have an R.-F. magnetic field which has a component along the longitudinal axis of the cavity 10. Since the TE_{0nm} modes are tunable (that is, their resonant frequency may be varied) by changing the length L of the cavity 10, the cavity length L is chosen so that the cavity 10 is resonant at $2f$ in some TE_{0nm} mode. The position of the ferrite element 19 along the axis is then chosen to excite this TE_{0nm} mode. In the device of the drawing, the length L of the cavity 10 is chosen to be resonant at the TE_{012} mode. The length L of the cavity 10 may be conventionally varied by a threaded member 40. An illustrative portion of the R.-F. magnetic field in the TE_{012} mode is shown by the dashed lines 30 in FIGURE 1.

Double-frequency energy in the cavity 10 may be conventionally extracted by means of an iris 51 and waveguide arm 57 by locating the iris 51 at a point of strong R.-F. magnetic field in the TE_{012} mode at the double frequency $2f$. To prevent input frequency energy from appearing in the output, it is preferable to have the cut-off frequency of the waveguide arm 57 above the input frequency f . Suitable points of strong R.-F. magnetic field in the TE_{012} mode are well known in the art.

It is important to note that the operation of the novel cavity device of the drawing is based on the fact that the resonant frequency of the cavity 10 in the TM_{110} mode is dependent only on the diameter and is totally independent of the length L . It is thus possible to adjust the dimensions of the cavity 10 so that the double frequency magnetic flux will excite a resonant TE_{0nm} mode at the double frequency. The frequency at which a cylindrical cavity resonates in a TE_{0nm} mode is dependent upon both the diameter and the length L . Once the diameter has been chosen so that the cavity 10 resonates in a TM_{110} mode at the input frequency f , the length L is then chosen so that the cavity 10 also resonates in a TE_{0nm} mode at the frequency $2f$.

It is also important to note that even though a cavity has the proper dimensions to resonate in a particular mode, it will not resonate in that mode unless the mode is excited. In the present invention, excitation in the TE_{0nm} mode is accomplished because it has an R.-F. magnetic field component along the axis of the cylindrical cavity. Thus, the ferrite element 19 can be positioned along the axis so that the double-frequency magnetic flux which is produced excites this TE_{0nm} mode.

It has been found that the double-frequency magnetic flux obtained is maximum when the magnitude of the D.-C. magnetizing field H_{d-c} is at either of the half-power

points of the ferromagnetic resonance curve. However, fields slightly further from ferromagnetic resonance should be chosen because as is well known, the ferrite element 19 absorbs a considerable amount of the input energy in the vicinity of resonance, thereby lowering the effective Q of the activity 10. The choice of the D.-C. magnetizing field H_{d-c} , therefore, will be some compromise value dependent upon the magnitude of input power, the Q of the cavity 10, and matching considerations. The important requirement is that the percentage of the input energy converted to double-frequency energy be maximized. Those skilled in the art will readily be able to provide the proper adjustments for satisfactory operation.

A specific example of a device constructed in accordance with the invention for frequency-doubling from about 9000 to 18,000 megacycles employs a cylindrical cavity 10 having a diameter of about 1.6 inches and a length L of about 0.758 inch. The ferrite element 19 comprises a ferrite rod about 0.2 inch long with a diameter of about 0.1 inch. The rod is disposed along the axis of the cylindrical cavity about 0.19 inch from one end. The input waveguide arm 14 is centrally located between both ends of the cavity 10, and the output arm 57 is located about 0.19 inch from the other end at a point of strong R.-F. magnetic field in the excited TE_{012} mode.

Although a cylindrical cavity has been used in the drawing to illustrate the invention, it will be understood by those skilled in the art that this invention can readily be extended to a rectangular cavity.

It will be apparent that the embodiments shown are only exemplary and that various modifications can be made in construction and arrangement within the scope of the invention as defined in the appended claims.

We claim as our invention:

1. A frequency-doubling microwave cavity device comprising in combination: a microwave cavity having dimensions such that the cavity is resonant in the TM_{110} mode at the frequency f and in a TE_{0nm} mode at the frequency $2f$, means for exciting said cavity in said TM_{110} mode at the frequency f , a ferrite element disposed within said cavity, a D.-C. magnetizing field applied to said ferrite element, the location of said ferrite element and the strength and direction of said D.-C. field being such that TM_{110} mode energy produces double-frequency magnetic flux which excites said TE_{0nm} mode, and means for ex-

tracting the double-frequency TE_{0nm} energy from said cavity.

2. A frequency-doubling microwave cavity device comprising in combination: a microwave cavity having a longitudinal axis, said cavity having dimensions such that the cavity is resonant in the TM_{110} mode at the frequency f and in a TE_{0nm} mode at the frequency $2f$, means for exciting said cavity in said TM_{110} mode at frequency f , a D.-C. magnetizing field applied to said cavity parallel to said longitudinal axis, a ferrite element disposed within said cavity along said longitudinal axis, the strength of said D.-C. field and the position of said ferrite element along said axis being such that TM_{110} mode energy produces double-frequency magnetic flux which excites said TE_{0nm} mode, and means for extracting the double-frequency TE_{0nm} mode energy from said cavity.

3. A frequency-doubling microwave cavity device comprising a cylindrical microwave resonant cavity having a longitudinal axis, said cavity having a predetermined diameter such that the cavity is resonant in the TM_{110} mode at an input frequency f , means for adjusting the length of the cavity so that the cavity is simultaneously resonant in a TE_{0nm} mode at an output frequency $2f$, input waveguide means coupled to said cavity for exciting said cavity in said TM_{110} mode, means for applying a D.-C. magnetizing field to said cavity parallel to said longitudinal axis, ferrite means responsive to said D.-C. field and to TM_{110} mode energy for producing double-frequency magnetic flux, means for mounting said ferrite means within said cavity along said longitudinal axis so that said double-frequency magnetic flux excites said TE_{0nm} mode, and output waveguide means coupled to said cavity for extracting the double-frequency TE_{0nm} mode energy from said cavity, said output means having a cut-off frequency above the input frequency f .
